(57) **CLAIM**

The ornamental design for a magnetic core, as shown and described.

DESCRIPTION

FIG. 1 is a front elevation view of a magnetic core, showing our new design;

FIG. 2 is a back elevation view thereof;

FIG. 3 is a left side elevation view thereof;

FIG. 4 is a right side elevation view thereof;

FIG. 5 is a top plan view thereof;

FIG. 6 is a bottom plan view thereof; and

FIG. 7 is a top, back, left side perspective view thereof.

FIG. 8 is a front view of embodiment 2 of the new design;

FIG. 9 is a back view of embodiment 2 of the new design;

FIG. 10 is a left view of embodiment 2 of the new design;

FIG. 11 is a right view of embodiment 2 of the new design;

FIG. 12 is a top view of embodiment 2 of the new design;

FIG. 13 is a bottom view of embodiment 2 of the new design;

FIG. 14 is a perspective view of embodiment 2 of the new design;

FIG. 15 is a front view of embodiment 3 of the new design;

FIG. 16 is a back view of embodiment 3 of the new design;

FIG. 17 is a left view of embodiment 3 of the new design;

FIG. 18 is a right view of embodiment 3 of the new design;

FIG. 19 is a top view of embodiment 3 of the new design;

FIG. 20 is a bottom view of embodiment 3 of the new design;

FIG. 21 is a perspective view of embodiment 3 of the new design;

FIG. 22 is a front view of embodiment 4 of the new design;

FIG. 23 is a back view of embodiment 4 of the new design;

FIG. 24 is a left view of embodiment 4 of the new design;

FIG. 25 is a right view of embodiment 4 of the new design;

(Continued)

FIG. 26 is a top view of embodiment 4 of the new design; FIG. 27 is a bottom view of embodiment 4 of the new design; and, FIG. 28 is a perspective view of embodiment 4 of the new design.

1 Claim, 28 Drawing Sheets

UNITED STATES PATENT AND TRADEMARK OFFICE
CERTIFICATE OF CORRECTION

PATENT NO. : D912,626 S
APPLICATION NO. : 29/697318
DATED : March 9, 2021
INVENTOR(S) : Haibin Song et al.

Page 1 of 8

It is certified that error appears in the above-identified patent and that said Letters Patent is hereby corrected as shown below:

On the Title Page

On page 2, Column 1 delete “1 Claim, 28 Drawing Sheets” and insert --1 Claim, 7 Drawing Sheets--.

In the Drawings

FIGS. 1-28 are shown, corrected figures should be FIGS. 1-7, as shown on the attached drawing sheets.

Signed and Sealed this
Twenty-first Day of December, 2021

Drew Hirshfeld
*Performing the Functions and Duties of the
Under Secretary of Commerce for Intellectual Property and
Director of the United States Patent and Trademark Office*
